DESIGN FOR A CARPET.

SPECIFICATION forming part of Design No. 15,407, dated September 16, 1884

Application filed August 6, 1884. Term of patent 3½ years.

To all whom it may concern.

Be it known that I, JAMES L. FOLSOM, of Brooklyn, New York, have invented a new and original Design for Carpets, of which the following is a specification, reference being had to the accompanying photograph, which forms a part of the same.

The invention relates to a design to be worked into or upon surfaces, such as carpets or similar fabrics; and it consists in the novel configuration and grouping of figures herein specifically shown and claimed.

The accompanying photograph is a face view of a carpet showing my new design.

The design, which is clearly shown in detail in the accompanying photograph, consists of various regularly-shaped gem and other figures, with smaller right-lined geometric figures closely filling in the ground between them.

I claim—

The design for a carpet, substantially as shown and described.
